SETTEE

Richard D. Williams, Toledo, Ohio, assignor to
 The Hettrick Manufacturing Company, Toledo,
 Ohio, a corporation of Ohio

Application February 9, 1951, Serial No. 14,151

Term of patent 14 years

(Cl. D15—11)

To all whom it may concern:

Be it known that I, Richard D. Williams, a citizen of the United States and a resident of Toledo, Lucas County, Ohio, have invented a new, original, and ornamental Design for a Settee, of which the following is a specification, reference being had to the accompanying drawing, forming a part thereof.

In the drawing:

The ornamentation of the rear and opposite side is similar to that of the front and side shown. The characteristic features of my design reside in the portions shown in full lines in the drawing.

I claim:

The ornamental design for a settee, as shown and described.

RICHARD D. WILLIAMS.
